MOISTURE DETERMINING APPARATUS

Richard T. Bell, Outremont, Quebec, Canada

Application December 18, 1939, Serial No. 309,802

3 Claims. (Cl. 73—51)

This invention relates to apparatus for determining the bulk specific gravities of saturated surface dry material and the moisture content of any known quantity of moist material such as sand, gravel, coal, pulp, ore concentrates, grain, etc.

According to one feature of this invention, the moisture content of a sample of moist material is determined by a method which consists in placing in a test vessel a quantity of moist material of a known weight, adding a given volume or known weight of water to the moist material so that the combined volume of the two will cause the water to reach a certain level in the gauge glass in the neck of the test vessel.

Another feature of my invention is to provide an adjustable apparatus for determining the moisture content of any known quantity of moist material.

Other features of this invention will be more readily understood from the following description taken in connection with the accompanying drawings, in which—

Fig. 1 is a front sectional view of the apparatus embodying my invention.

Fig. 2 is a fragmentary front elevational view of the apparatus shown in Fig. 1, this view showing the moisture and specific gravity gauges secured to the neck of the flask.

Fig. 3 is a sectional view through the line 3—3 of Fig. 2.

Fig. 4 is a fragmentary perspective view showing a modified form of the apparatus shown in Fig. 2.

Fig. 5 is a plan view of a moisture index scale and an associated auxiliary gravity index scale forming part of said apparatus.

Fig. 6 is a plan view of the apparatus disclosed in Fig. 1.

As illustrated in the accompanying drawings, 40 5 designates a receptacle having lug portions 6 on either side at the top. Clamping bolts 7, provided with thumb screws 8, are hingedly mounted in lugs 6 for securing lid 9 to the top of the receptacle 5. A circular groove 10 is provided in the top of the receptacle 5 and a washer 11 is mounted therein which seals against the face of the lid 9 adjacent the receptacle 5. The lid 9 is provided with a circular neck portion 12 which is cut away at the front and rear as indicated at 13 and 14. The neck portion 12, therefore, forms two side walls which support a gauge glass 15. The gauge glass 15 rests on a ledge 16 within an opening 17 in the lid 9 and is preferably cemented to the ledge 16.

The right side of the neck 12 is provided with a calibrated plate 18 which carries specific gravity

index markings. The plate 18 may be fastened at any portion throughout the length of the front face of the neck 12 when the vessel is calibrated. Over the neck 12 is placed a slide or cursor 19 which is adjustably positioned on the neck 12 by set screw 20. The cursor 19 is provided with circular bands at top and bottom, the side walls defining front and rear vision openings corresponding with the openings 13 and 14 of neck 12, and slides over the plate 18. A moisture percentage indexed plate 21 is secured to the left hand front face of the cursor 19 between the top and bottom circular bands.

As shown in Fig. 4, the moisture percentage indexed plate 21 may be provided with an extension plate 24 which is folded as indicated at 25, the extension plate 24 being curved to fit around the left hand side wall of the cursor 19. The plate 24 is provided with specific gravity readings and a transparent spring clip marker 26 or other suitable means is slidably mounted on the cursor 19.

The method of operation is as follows: First, for bulk specific gravity (saturated surface-dry basis), the flask or test vessel is used as an ordinary specific gravity flask, i. e., a quantity of known weight of saturated surface dry material is placed in the lower portion of the test vessel 5; the cover or lid 9 and neck 12 which are in one piece is then placed in position and the thumb screws 8 tightened to prevent leakage. A known weight or volume of water is then poured into the test vessel through the gauge glass 15. The vessel is then well shaken to release all entrained air.

The bulk specific gravity can then be read on the gauge 18 attached to the neck of the vessel at the height to which the water reaches in the gauge glass 15.

The designation "bulk specific gravity" (saturated surface dry basis) is used in accordance with A. S. T. M. Designation E. 12 of the American Society for Testing Materials, which is as follows:

45 Bulk specific gravity saturated surface dry basis

The bulk specific gravity, on the weight of saturated surface dry aggregate, shall be calculated from the following formula,

$$\text{Bulk specific gravity} = \frac{B}{B-C}$$

where

B=weight in grams of surface dry saturated sample in air

C=weight in grams of surface dry saturated sample in water.

This formula differs from that for apparent specific gravity, which is based on oven dried material.

In computing bulk specific gravities for calibrating the specific gravity index plate attached to the receivable 5, specific gravity=1 has been taken as one cubic foot of water (1728 cubic inches) weighing 62.415 lbs. at a temperature of 3° centigrade.

The volume of 4 lbs. of water or any other desired weight may be calculated from the following formula,

$$\text{Cubic inches} = \frac{A}{B} \times C$$

where

A=weight of water

B=specific gravity 1=1 cubic foot of water weighing 62.415 lbs. at 3° centigrade

C=1728 cubic inches in 1 cubic foot.

Substituting values for a four pound weight of water,

$$\frac{4}{62.415} \times 1728 = 110.742 \text{ cubic inches, the volume of 4 lbs. of water.}$$

For computing the volume for materials of various specific gravities the following formula is used,

$$\text{Cubic inches} = \frac{D}{E}$$

where

D=110.742

E=specific gravity.

Substituting values for specific gravity "2.0

$$\frac{110.742}{2.0} = 55.371 \text{ cubic inches the volume of a 4 lb. sample of material with a specific gravity of 2.0.}$$

The range of specific gravities required are computed in this manner and the index marks on the gauge so calibrated, adding whatever number of cubic inches of water it is desired to use. As an example with two pounds of water added we have,

	Cu. ins.
4 lb. sample of material specific gravity 2.0	55.371
2 lb. water added	55.371
In test vessel	110.742

To ascertain the amount of water present in moist sand or other material of known bulk specific gravity, a sample of definite weight is placed in the lower portion of the test vessel, and a known weight or volume of water is added thereto. The cursor 19 is then adjusted until the zero mark on plate 21 coincides with the graduation mark on plate 18 representing the specific gravity of such material when free of moisture. The height to which the water rises in tube 15 is then read off on plate 21 and represents that difference between the bulk of the dry material and the moist material which is due to the amount of moisture present in the moist material, the plate 21 being graduated in terms of the percentage of moisture in the material.

Having established the total volumes for the various bulk specific gravities incidental to the gravel, sand and other concrete aggregates, i. e. from 2.5 to 2.9 to arrive at the total volume of dry aggregate and water in a sample of a known

weight containing various percentages of moisture, the following formula is used:

$$\text{Aggregate } \frac{A}{C \times E} \times D = \text{cubic inches}$$

$$\text{Water } \frac{B}{C} \times D = \text{cubic inches}$$

where

A=the amount of dry aggregate in sample

B=the amount of water in sample

C=62.415 lbs. the weight of 1 cubic ft. of water

D=1728 cubic inches

E=the specific gravity of the material under test.

As an example a 4 lb. sample of moist material containing 10% of water and having a specific gravity of 2.0, the 4 lb. sample will consist of 90.9091% material and 9.0909% of water.

$$4 \times 90.9091\% = 3.6364 \text{ lbs. material}$$

$$4 \times 9.0909\% = 0.3636 \text{ lbs. water}$$

Substituting figures

$$\text{Material } \frac{3.6364}{62.415 \times 2.0} \times 1728 = 50.337$$

$$\text{Water } \frac{0.3636}{62.415} \times 1728 = 10.067$$

$$\begin{array}{rcl} \text{Total} & \dots & 60.404 \\ 30 \text{ Add two lbs. water} & \dots & 55.371 \end{array}$$

$$\text{Total in test vessel} \dots 115.775$$

In the present instance the specific gravity index plate 18 is shown graduated in terms of specific gravities ranging between 2.5 and 2.9 since, in actual practice, few, if any, concrete aggregates have specific gravities below or above these figures. The moisture percentage index plate 21 is graduated in terms of moisture percentages ranging from 1 to 12 percent.

If greater exactitude is required use is made of the auxiliary specific gravity index scale carried by the extension plate 24. The gauge glass 15 is correct for specific gravity reading of 2.64 which is the average specific gravity for commercial purposes. However, if the specific gravity of the substance should be, for example, 3.0 and the moisture content was indicated as 10% by reading along the marker 26 to the line indicated at a specific gravity of 3, the exact moisture percentage could be determined. For instance, instead of being 10% at S. G. 2.64 the moisture content would be 9.4% at S. G. 3. It will readily be seen therefore that exact moisture percentages can be determined for any of the specific gravities between 2.6 and 3.0. It is obvious that the plate 24 may be provided with a much wider range of specific gravity readings.

Another modification would be to provide separate gauge plates 18 for each and every specific gravity.

Instead of the openings provided in the side walls of the cursor 19, these side walls may be made transparent.

Having thus described my invention, what I claim is:

1. Apparatus for determining the bulk specific gravities of saturated surface dry materials and the moisture content of moist materials of known specific gravity comprising a receptacle provided with a cover having a tubular member extending upwardly therefrom, said tubular member surrounding an opening formed in said cover and being provided with a sight opening, a transparent gauge tube arranged in said tubular member

and communicating with the interior of said receptacle, an index plate secured to said tubular member at one side of said sight opening, said index plate being graduated in terms of specific gravity, a cursor slidably mounted on said tubular member for movement longitudinally thereof, and a second gauge or index plate carried by said cursor, said second gauge plate being graduated in terms of moisture content.

2. Apparatus for determining the bulk specific gravities of saturated surface dry materials and the moisture content of moist materials of known specific gravity comprising a receptacle provided with a cover, a transparent gauge tube rising from and rigidly secured to said cover, said tube being in communication with the interior of said receptacle, a calibrated index plate secured in a fixed position and extending along a portion of the gauge tube, said index plate being graduated in terms of specific gravity so that, when a quantity of known weight of saturated surface dry material is placed in the receptacle along with a known weight or volume of water, the bulk specific gravity of said material may be read directly from said index plate as the function of the height to which the water rises in the vessel, a cursor slidably adjustable along the length of the gauge tube and a second index plate fixed to

5 travel with said cursor, said second index plate being graduated in terms of moisture content and being calibrated so that when a measured quantity of moist material, whose specific gravity is known or has been ascertained by the use of the first mentioned index plate, is placed in the vessel along with a known weight or quantity of water, the moisture content of said moist material may be determined by adjusting the cursor until the zero mark on the second mentioned index plate coincides with that graduation mark on the first mentioned plate which represents the specific gravity of such material when free of moisture, the moisture content of said material being then readable on the second index plate at the level to which the water rises in said vessel.

10 15 20 25 3. Apparatus as set forth in claim 2 including an auxiliary specific gravity index plate attached to said cursor and an auxiliary cursor slidably mounted on said first mentioned cursor to facilitate the reading of said auxiliary gravity index plate, said auxiliary index plate and said auxiliary cursor being used when the approximate specific gravity readings of the first mentioned specific gravity index plate are not sufficiently accurate.
